UNITED STATES PATENT OFFICE.

EDWARD FRANK NEVINS, OF BLUE RAPIDS, KANSAS.

MOLD.

No. 808,167.

Specification of Letters Patent.

Patented Dec. 26, 1905.

Application filed April 17, 1905. Serial No. 255,994.

To all whom it may concern:

Be it known that I, EDWARD FRANK NEVINS, a citizen of the United States, residing at Blue Rapids, in the county of Marshall and 5 State of Kansas, have invented a new and useful Mold, of which the following is a specification.

This invention relates to molds, and has for its object to provide certain new and useful 10 improvements whereby the mold is particularly adapted for the production of sewer-pipes and the like. It is also proposed to form the body of the mold and the core in sections which are capable of being conveniently 15 assembled and set up for the reception of the material to be molded and also arranged to be conveniently disconnected and removed from the cast without liability of injury thereto.

20 With these and other objects in view the present invention consists in the combination and arrangement of parts, as will be hereinafter more fully described, shown in the accompanying drawings, and particularly pointed 25 out in the appended claims, it being understood that changes in the form, proportion, size, and minor details may be made within the scope of the claims without departing from the spirit or sacrificing any of 30 the advantages of the invention.

In the accompanying drawings, Figure 1 is a longitudinal sectional view of a mold embodying the features of the present invention. Fig. 2 is a cross-sectional view on the 35 line 2 2 of Fig. 1. Fig. 3 is a detail perspective view of one of the body-sections. Fig. 4 is a detail perspective view of one of the core-sections. Fig. 5 is a detail perspective view of the top member of the core. Fig. 6 is a detail perspective view of one of the cross-heads for connecting the core-sections.

Like characters of reference designate corresponding parts in each and every figure of the drawings.

45 As embodied in the accompanying drawings it will be seen that the body of the present mold is tubular in form and made up of two complementary longitudinal sections, each of which is designated 1 and is externally 50 enlarged at one end to form a bell portion 2. A series of slotted links 3 are hinged externally to one edge of the section, and upon the exterior of the opposite side of the section there is a series of keepers 4, preferably 55 in the nature of staples, which are designed to be received through the slots of the

corresponding links on the other section, so as to detachably connect the sections, as clearly indicated in Fig. 2 of the drawings.

The core member of the mold is tubular in 60 form and made up of three longitudinal sections, each of which is designated 5 and is provided upon its interior adjacent each end with opposite spring-clips 6, which are offset from the section and have their outer ends 65 substantially flush with the respective longitudinal edges of the core-section. By preference, these spring-clips are formed upon the ends of a metallic strip 7, soldered or otherwise secured to the inner face of the core- 70 section, with its ends bent or offset to form the spring-clips. When three of the core-sections are assembled, as shown in Fig. 2 of the drawings, the corresponding spring-clips register and constitute seats for the reception 75 of terminal lugs or projections 8 upon a substantially triangular cross-head 9, which is fitted into the core, so as to connect the core-sections at their inner faces, and thereby leave the exterior of the core free from projections.

In setting up the mold the body-sections 1 are connected and stood on end, with the bell portion 2 at the top, after which the core-sections are assembled and placed downwardly 85 through the open top of the body, or the core-sections may first be assembled and then the body fitted about the core. The core must of course be centered within the body, and then the material to be molded is poured into 90 the annular space between the core and the body until the level of the material nearly reaches the bell portion 2 of the body, whereupon the bell portion of the core is fitted in place upon the latter. This bell portion is 95 shown in Figs. 1 and 5 and consists of a band or cylindrical member 10, somewhat greater in diameter than the core and provided at its lower edge with an internal annular flange 11, the band and the flange being split or 100 separated, as indicated at 12. Suitable fingers or projections 13 depend from the inner edge of the flange 11. Upon the interior of the part 10 and at each side of the joint 12 there is a spring-clip 14, the two clips being 105 registered and constituting a seat for the reception of a key 15, which is provided at its upper end with a laterally-extended flange or head 16 for convenience in driving the key in place and in prying the same out of the 110 seat. The flange 11 is cleft radially at several points, as indicated at 17. With the

bell of the core assembled, as in Fig. 5, it is placed upon the top of the core, with the projections or fingers 13 fitting snugly the interior of the core, so as to hold the bell of the 5 core centered within the bell of the mold-body. After the inner bell member has been fitted in place the mold is entirely filled with the material and permitted to stand until it has become set, whereupon the body of the 10 mold and the core are removed.

In removing the core the bell portion is first removed, the key 15 being disengaged from the clips 14, and then one end of the split bell is forced radially inward and pulled 15 slightly outward, so that it may be drawn inwardly to overlap the other end of the bell, thereby to reduce the external diameter of the bell and permit of the latter being drawn out of the cast without damaging the interior thereof. It will now be understood that the flange 11 is cleft, as at 17, to permit of the necessary bending of the flange to permit of the compression of the bell prior to removing the same from the cast. The cross-heads 20 25 9 are then removed from their seats, so as to disconnect the core-sections and permit of the latter being conveniently drawn out of the cast. The body of the mold is of course removed by disengaging the slotted links 3 30 from the keepers, and may be removed prior to or after the removal of the core.

From the foregoing description it will be understood that the mold of the present invention is exceedingly simple and effective for 35 the purpose designed, and the several sections may be formed of sheet metal, so as to render the mold both durable and inexpensive. Moreover, the several sections may be conveniently connected and assembled when 40 setting up the mold and may also be readily disconnected and removed from the cast without liability of injury thereto.

Having fully described the invention, what is claimed is—

45 1. A pipe-mold comprising a tubular body having a bell terminal, a core member terminating short of the bell terminal of the body, and a core-bell member for removable engagement with that end of the core which is 50 adjacent the bell terminal of the body, the core-bell member capable of being contracted for withdrawing the same from a cast.

55 2. A pipe-mold comprising a tubular body having a bell terminal, a core member terminating short of the bell terminal of the body, a split tubular bell-core to be removably fitted to that end of the core which is adjacent the bell terminal of the body, registered seats upon the interior of the core-bell member at opposite sides of the joint of the bell, and a removable key capable of being fitted 60

in the seats to hold the bell in its normal condition, said bell capable of being contracted when a key is removed to permit removal of the bell from a cast.

65

3. A pipe-mold comprising a tubular body having a bell terminal, a tubular core terminating short of the bell terminal of the body, and a split tubular bell-core member of greater diameter than the core and provided 70 with an internal annular flange to rest against that end of the core which is adjacent the bell terminal of the body, and means upon the interior of the bell-core member to detachably connect the ends thereof, the flange 75 of the bell being cleft to permit contraction of said bell when the fastening means is released.

4. A pipe-mold comprising a tubular body having a bell terminal, a tubular core terminating short of the bell terminal of the body, a split tubular core-bell member having an internal annular flange to rest against that end of the core which is adjacent the bell of the body, projections upon the inner edge of 80 the flange to enter the core, registered seats upon the interior of the bell-core member at opposite sides of the joint thereof, and a removable key engaging the seats, the core-bell member capable of being contracted 85 when the key is removed to permit withdrawal of the bell.

5. A mold having a tubular core made up of separable longitudinal sections, seats upon the inner sides of the core-sections, and a 95 cross-head having means for detachable engagement with the seats to removably connect the core-sections.

6. A mold having a tubular core made up of separable longitudinal sections, registered 100 seats upon the interior of the core-sections at opposite sides of the joints thereof, and a cross-head having lateral projections for detachable engagement with the registered seats to removably connect the core-sections. 105

7. A mold having a tubular core divided into longitudinal separable sections, a band secured transversely within each core-section with its ends offset to form seats adjacent the edges of the section, the corresponding seats of the sections being registered when the sections are set up, and a cross-head having lateral projections to detachably enter the seats and removably connect the core-sections. 110 115

In testimony that I claim the foregoing as my own I have hereto affixed my signature in the presence of two witnesses.

EDWARD FRANK NEVINS.
